ATTORNEY.

UNITED STATES PATENT OFFICE.

FRANK HARVEY MILLER, OF MONTGOMERY, ALABAMA.

APPAREL.

1,404,465.

Specification of Letters Patent. Patented Jan. 24, 1922.

Application filed May 31, 1921. Serial No. 473,591.

To all whom it may concern:

Be it known that I, FRANK H. MILLER, a citizen of the United States, residing at Montgomery, in the county of Montgomery and State of Alabama, have invented certain new and useful Improvements in Apparel, of which the following is a specification.

This invention relates to improvements in apparel and while it was particularly devised to furnish an improved garment for children, nevertheless a garment constructed according to my invention, may be used for various purposes.

15 The principal object of the invention is to provide a garment of simple and inexpensive construction, which may be easily and speedily placed on or removed from the wearer.

20 A further object of the invention is to provide a bifurcated garment in which three buttons only will be sufficient for the purpose of securing the top of the jacket portion, waist and the rear panel of the trouser portion in place. More buttons may be 25 used if desired.

With the foregoing objects outlined and with other objects in view, which will appear as the description proceeds, the invention consists in the novel features herein-30 after described in detail, illustrated in the accompanying drawing and more particularly pointed out in the appended claims.

Referring to the drawings:

Fig. 1 is a perspective view of one form 35 of the garment as worn upon the person.

Fig. 2 is a rear view of one form and Fig. 3 of a different form, of the same, with the rear flaps and panel closed.

Fig. 4 is a rear view of the garment 40 shown in Fig. 3, with the flaps opened and the panel lowered.

Fig. 5 is a detail view of a slight modification.

Fig. 6 is a detail sectional view of the said 45 modification.

In the drawing, 1 represents as a whole, a bifurcated union garment which, in the present instance, comprises a shirt or jacket portion 2, having a solid or unbroken front 50 and a back formed of a plurality of overlapping flaps 3 and 13. One of the flaps, namely the inner flap 13, has an outwardly inclined side edge 4 and an arc shaped lower edge 5, the length of the latter being substantially the same as the distance between 55 the opposite sides of the garment. The edge

of the outer flap 3 may be nearly vertical from the top button hole 15^a to the bottom button hole 16^a.

The garment also includes a trouser portion 6, the upper edge of the front of which is stitched to or integral with the lower edge of the front of the shirt portion and a waist band 7 is provided between these edges. This waist band is provided in the 60 preferred embodiment of my invention, as shown in Figs. 1 to 3, inclusive, with two buttons 8 and 16 which are arranged at the opposite sides of the waist band. The flaps 13 and 3 of the shirt portion of the garment, are provided at their corners with button holes 9 and 16^a which, when the flaps are overlapped, are designed to engage with the buttons 8 and 16, respectively, for the purpose of holding the flaps in overlapped 65 positions to form the rear of the shirt portion.

At some place on the neck or back of the shoulder or top of the shoulder, a button hole 15^a is provided to engage a button 15, to make 80 the garment fit tightly around the back of the neck, and prevent cold drafts, etc., from striking the wearer at that place. Also it acts to cover up and thus hide the back of the neck. In this feature the present invention is an improvement on the disclosure of my co-pending case, Serial No. 417,315, filed October 16, 1920. In Figs. 1 and 2, this third button is shown on the side, namely, over one shoulder while in Figs. 3 and 4, 85 it is shown at the middle of the back of the neck.

The trouser portion 6 is provided with a drop flap or panel 10 provided at its corners with button holes 11 designed to receive the 90 buttons 8 and 16, after the flaps 13 and 3, respectively, have been secured to the same.

In the modification shown in Figs. 3 and 4, the two back flaps of the jacket portion are cut alike, and the button 15 and button hole 100 15^a come at the middle of the back of the neck. This makes a neater garment.

From the foregoing I believe the basic idea of my invention will be readily understood, but to render the same absolutely 105 clear, I may state that in placing the garment on the wearer, the legs are first placed through the bifurcated portion of the trousers 6, the arms are then inserted in the sleeves 22, and then the flaps 13 and 3 are 110 folded and overlapped across the back and secured to the buttons 8 and 16, respectively.

Finally, the rear flap or panel 10 is moved upwardly and secured to the buttons 8 and 16. It will be noted that the arc-shaped edges project below the waist line, when the flaps are overlapped, and this downwardly extending part prevents exposure to the person should the panel 10 sag.

In the modification of the invention shown in Figs. 5 and 6, the buttons 8^a instead of being secured to the waist band, are provided at the corners of the flap 13^a (and correspondingly on the other flap), and the waist band 7 and panel 10 are provided at the two sides with button holes 9^a and 11^a through which these buttons are inserted. With this construction, the flap 13^a and the other flap are overlapped across the back and the buttons at the ends of said flaps are inserted through the button hole 9^a and the corresponding button hole on the other side, and finally the buttons are placed through the button hole 11^a (and the button hole at the other end of the panel) to hold the rear panel in place, or the end of one flap 13^a can be thus arranged with a button and the end of the other corresponding flap with a button hole as first described.

If desired, one or more additional buttons may be provided, as shown at 12, on the back 30 of the belt or waist band, to secure the panel from sagging. These, of course, would operate with button holes 11^b.

While I have described and illustrated several preferred embodiments of my invention, I am aware that various changes and modifications may be made in the embodiment shown without departing from the spirit of the invention as set forth in the claims.

40 The invention possesses the following advantages over garments now in general use. First, it is of simple design and easily donned or removed. Second, the construction is suitable for union underwear for adults 45 and children and it may be used in making outer garments for children as well as working suits and overall suits for adults. Third, it can be placed on the wearer without putting the garment over the head. Fourth, 50 the overlapping flaps at the rear provide extra warmth for the kidneys and vital organs in cold climates, while affording additional protection to the spine in hot climates. Fifth, the entire suit can be fastened on with 55 a minimum of three buttons, easily accessible. Sixth, the lower edges of the two overlapping flaps, preferably extend below the waist line, so as to keep the body protected in case the top of the drop flap when buttoned, should 60 sag across the back. Seventh, the back flap or drop panel may be provided with additional button holes, so that the waist may be readily adjusted to accommodate persons of different sizes.

65 The above advantages are mostly common

in this and the co-pending case above referred to. In the present case, by the third button at the top, the device is an improvement over that of my prior application, since the back of the neck is protected and a 70 neater garment is provided.

It is, of course, obvious that a collar or other trimming, pockets, etc., can be provided if desired.

What I claim and desire to secure by Letters Patent is:

1. A bifurcated garment including a shirt portion and a trouser portion, the shirt portion being provided with overlapping flaps, each flap extending from the top of the garment to the waist line and having a lower edge which extends from one side of the garment to the opposite side, a drop rear panel provided at the rear of the trouser portion, and a single fastening means connecting a corner of the panel and a corner of one of said flaps to the waist line portion of the garment at one side of the garment, the upper parts of said two flaps buttoning together. 90

2. A union garment including an upper shirt portion and a lower portion connected thereto by a waist band, the shirt portion being provided with overlapping flaps, each flap extending from the top of the garment to the waist line and having a lower edge which extends from one side of the garment to the opposite side, the lower portion being provided with a drop panel, fastening means securing the corners of the flaps and the 95 corners of said panel to the waist band portion of the garment at the sides of the garment, and fastening means for fastening the tops of the said flaps together. 100

3. A bifurcated union garment including a shirt portion and a trouser portion, the shirt portion being provided at its rear with overlapping flaps, each of which is provided with a downwardly and outwardly inclined side edge and a downwardly projecting lower edge, the lower edge extending from one side of the garment to the opposite side, the rear of said trouser portion being provided with a drop panel, and fastening means securing the lower corners of the 110 flaps and the corners of said panel to the waist band of the garment at the sides of the garment, the upper ends of said flaps meeting each other at the neck, and securing means at the said meeting point. 115

4. A bifurcated union garment including a waist portion having a waist band, overlapping flaps forming part of the waist portion and provided at the rear of the garment, each flap extending from the top of the garment at the neck to the waist line and having a lower edge which extends from one side of the garment to the opposite side, a trouser portion, a drop panel for the trouser portion, and a single securing means for se- 125 130

curing one of the lower corners of one of said flaps and one of the corners of the panel to the waist band of the garment at one side of the garment, and means for securing the 5 tops of said flaps to each other.

5. A bifurcated garment including a waist portion having a waist band, overlapping flaps forming part of the waist portion and provided at the rear of the garment, each 10 of said flaps having a side edge which is inclined downwardly and outwardly from a little to one side of the middle of the neck portion to the opposite side of the waist band, and each flap having a lower edge 15 which extends from one side of the garment to the opposite side, a trouser portion hav-

ing its front secured to the waist band and its rear provided with a drop seat panel having an upper edge which extends from one side of the garment to the other side, a single fastening means connecting the corner of one flap to one of the corners of the drop seat panel, and a single fastening means connecting the corner of the other flap to the other corner of the panel; and a fastening means for securing the tops of the two flaps together at the back of the neck, said fastening means constituting the only fastening for securing the garment on the wearer's body.

In testimony whereof I affix my signature.
FRANK HARVEY MILLER.
